ABRAHAM PODEL, OF LONG ISLAND CITY, NEW YORK, ASSIGNOR TO ANCHOR CAP AND CLOSURE CORPORATION, OF LONG ISLAND CITY, NEW YORK, A CORPORATION OF NEW YORK.

STACKING MACHINE.

Application filed January 2, 1924. Serial No. 683,930.

The present invention relates to machines for handling sheet material and more particularly to machines for automatically receiving and stacking sheets of metal or the like.

5 The general object of the present invention is the provision of a machine adapted to receive sheets of metal, commonly used in the manufacture of containers and covers, from a conveyor or the like and to stack the 10 sheets to facilitate their ready removal from one machine to another with a minimum of manual labor.

Another object of this invention is to provide a machine properly timed with respect 15 to a conveyor to receive sheets of material moving thereon and to place them on a truck or the like.

Another object is to provide a mechanism adapted to receive sheets of tin or the like 20 from a conveyor and to transfer them to a stack supported and maintained at a substantially constant height with respect to the machine so that the sheets of tin will fall a substantially constant distance, which is as 25 small as possible.

Another object of the invention is to provide a mechanism in such a machine which will utilize the movement of the conveyor 30 mechanism to maintain the top of the stack plates at a predetermined level, irrespective of the increase in level caused by the additional plates stacked thereon; to do this by rendering ineffective the table lowering mechanism when the top of the stack of 35 plates has been lowered beyond a predetermined level.

A further object of the invention is to provide a stacking machine wherein the stack of plates is automatically lowered to a truck for 40 the ready removal thereof from the machine; to provide an automatic cut out for rendering the lowering mechanism ineffective when the table, upon which the stack of plates rests, is at a proper height to be mounted on 45 the truck.

Further objects of this invention contemplate a machine of the above characteristics, which is of such strong and simple construction and such accurate operation as to insure 50 its proper performance under all conditions commonly encountered in this class of work; to provide a machine which will greatly minimize the amount of labor required in mov-

ing sheets of tin or the like from one machine to another either during the making of 55 the tin itself or during its manufacture into marketable articles.

Other and further objects of the invention will be obvious upon an understanding of the illustrated embodiment about to be described, or will be obvious from the accompanying drawings, or indicated in the appended claims; and various advantages secured by the invention other than those hereinafter specifically referred to will occur to 60 one skilled in the art or become evident upon the employment of the invention in practice.

In the drawings Figure 1 is a front elevational view of the machine;

Figure 2 is an end view of the preferred embodiment;

Figure 3 is a top plan view;

Figure 4 is a detailed end view of a portion of the machine;

Figure 11 is a cross-sectional view along lines 11—11 of Figures 1 and 12 showing the details of the automatic control for the plate supporting means; and

Figure 12 is a detail view of a part of the 95 automatic control for the machine.

In the manufacture of metal caps and containers it is necessary to subject the tin used to several treatments necessitating its passage through various machines; for 100 example, the sheets must be thoroughly cleaned, lacquered, and passed through a series of printing presses, and finally run through the various stamping operations necessary to construct the desired articles. 105 Usually the above steps do not follow con-

secutively but a considerable period of time elapses between each, making it necessary for the great mass of tin not only to be moved from one machine to another, but to be stored frequently in other parts of the building. Heretofore in the art it has been customary to manually receive the sheets of tin from a conveyor and place them on a truck. This required at least one man at each machine to receive the sheets and another to move the tin after it was placed on trucks. Obviously this required a great expenditure of labor in addition to other difficulties occasioned by the tin not being evenly stacked.

The present invention eliminates the above disadvantages by providing a stacking machine completely automatic in all its operations. It receives the tin from the usual conveyor, stacks it evenly upon a table adjustable in height and lowers the table on a suitable truck when a predetermined quantity of tin has been placed thereon. The truck and the table may then be removed and another replaced without affecting the operation of the stacking machine in any manner.

Referring generally to preferred embodiment of the machine, these results are accomplished by providing a rigid frame work at the end of a suitable conveyor having collapsible sheet supporting members adapted to receive individual pieces of tin. When properly positioned the sheet of tin is permitted to drop to the stack as these members are collapsed by the conveyor. A suitable table is provided to receive the tin and suitable mechanism is interposed between the table and conveyor to utilize the motion of the conveyor to retain the table at the desired height. In this manner, the top of the stack is always slightly below the collapsible members which receive the tin from the conveyor; and the distance the tin drops is always a minimum. Suitable safety devices are attached to the machine to prevent the table from moving beyond certain predetermined positions. Auxiliary supporting members are provided for retaining the tin while the main table is being removed and replaced. Automatic means are provided for controlling the position of the table and the height of the tin while rendering the table lowering mechanism ineffective when the top of the stack drops below a predetermined level. Other advantageous features will appear in the more detailed description following.

Referring to the drawings and more particularly to Figures 1, 2, and 3, there is provided a stacking machine 1, embodying one form of the present invention, operatively connected to a conveyor 2. A pair of upright channel members 4 are suitably mounted by bolts 5 upon a pair of base plates 6

which are in turn secured to the floor or foundation by means of bolts 7 extending through their ends. The upper portions of the upright members are joined by a beam 8, which acts as a brace, and which is securely fixed by the bolts 9 to the ends of the upright members. Additional bracing and supporting members 10 are securely fixed at the central portions of the upright members by bolts 11. The supporting members 10 in addition to their other functions permit sheets of metal to fall therebetween and also provide suitable supports for the attachment of various mechanisms herein-after described for the proper automatic operation of the entire machine.

A pair of shafts 12 threaded at their lower end 13 are mounted within the channels of the upright members 4. The lower ends of these may extend into the base plate 6 and be mounted on ball bearings as shown at 14 to decrease the friction between the shafts and the base plates. The upper ends of the shafts extend through suitable bearings 15 in the ends of the cross beam 8. A pair of L-shaped members 16 are threaded to the shafts 12 to move upwardly as the shafts are turned. The horizontal portions 17 of the L-members 16 furnish supports for a table 18 which may comprise a metallic plate or the like upon which the tin or other material is evenly stacked. A hand wheel 19 having a handle 20 is operatively connected to one of the shafts 12 through the bevel gears 21 and 22 mounted on the shaft 24 and the center of the hand wheel 19 respectively. The table supporting shafts 12 are geared to each other through the shaft 25 by means of having gears 26 and 27 meshing at all times with the bevel gears 28 on the vertical shafts 12. The table 18 can be raised or lowered by means of the hand wheel 19 independently of the operation of the machine. Hand operation is preferable in raising the table to its upper position for receiving sheets of tin and it is frequently utilized in lowering the table upon the truck. Automatic devices are provided for maintaining the table at a proper height to receive the tin. These will be described hereinafter.

While the sheets of tin or other material may be supplied in any suitable manner, the stacking machine herein is shown receiving sheets of tin from a conveyor mechanism of the usual type, a sufficient portion of which is shown to illustrate the application of the present invention to machines and conveyors generally. Referring to the drawings and more particularly to Figures 1 and 2, there is shown a pair of vertical supports 30 having suitable bearings 31 adapted to receive a shaft 32. A pair of cog-wheels 34 mounted on the shaft 32 carry belts or chains 35 having projections

36 adapted to engage the sheets of metal and move them toward the stacking machine, delivering one sheet of metal per revolution of the cog wheel 34. Suitable 5 pulleys 37 may engage the lower portions of the chains or belts 35 to take up any slack therein. These pulleys 37 are attached preferably to the vertical supports 30 by means of an arm 38 rotatably adjustable 10 to vary the tension in the belts. Supplemental conveyor belts 39 are provided on pulleys 40 mounted on shaft 32 and are adapted to engage the sheets of tin which are moving on the chains 35 and move them 15 at a slightly greater speed than the speed of the chains in order to move the edges of the respective sheets away from the projections 36 on the chains 35. In case a slight resistance should be encountered 20 such as passing between rollers as the sheets are being removed from the conveyor, sufficient time will be given to prevent the projections 36 from bending the tin, as would be the case if they were in engagement there- 25 with at the time the resistance to the movement of the tin is encountered. The other end of the conveyor mechanism may be similar to the one described and a detailed explanation is unnecessary.

30 The sheets of tin 42, shown in dotted lines in Figure 1, are carried by the chains 35 and belts 39 to the stacking machine 1, and moved on the collapsible plates 41 until their forward edges touch the stops 35 44. The sheets when in this position are ready to be dropped to the stack supporting table 18 between the guides 43^a by means of coordinated mechanisms about to be described. The height of the stack is 40 automatically controlled by mechanisms which are shown connected to the conveyor mechanism.

The power for the operation of the stacking machine, may for convenience, be obtained by gearing the various mechanisms to the conveyor shaft 32, by operatively connecting same to the clutch box 45 which is provided with a removable cover 43 and mounted on the supporting members 10. 45 The shaft 32 is permanently attached to shaft 46 in the gear box 45 through interlocking jaws 47. A gear 48 of the clutch is mounted on the shaft 46 and meshes with gear 49 loosely mounted on shaft 50, which has its end in the form of a jaw 51. A 50 cooperating jaw 52 is formed in the end of the member 54 which is slidably, but not rotatably mounted on the shaft 50. The cooperating jaws 51 and 52 form a clutch for throwing the power on and off the stacking machine. A handle 55 rigidly mounted on a guide shaft 56, which is adapted to slide in the bearing 57 and 58, operates this clutch. The lower end of the handle 55 is 55 bifurcated to extend around the power shaft

46 and engage the slidable member 54 on the shaft 50 as shown in Figures 5 and 6 wherein the clutch is disengaged. Suitable notches 59 and 60 are provided in the guide shaft 56 and are adapted to be engaged by 70 resilient retaining members 61 adjustably held in place by threaded screws to positively hold the clutch either in engaged or disengaged position, and thereby eliminate the possibility of the clutch being jarred 75 out of position in any instance.

The shaft 50 mounted in the bearings 62 and 64 of the clutch box 45 has a cam 65 rigidly mounted thereon by means of the bolt 66. A cam follower 67 is attached to the reciprocating member 68 by means of the bolt 69. The necessary power for operating the stacking mechanism is transmitted through cams 65 to the reciprocating member 68 which is slotted at 70 to fit on the shaft 50 and to be guided thereby. A spring 71 retains the cam follower in contact with the cam at all times. The upper end of a lever 72 extending through the reciprocating member 68 is connected to the 80 arm 74, extending from shaft 75, by a suitable bolt 76 to oscillate the shaft 75 continuously during the operation of the stacking machine 1.

The shaft 75 may be mounted in bearings 77 attached to upright members 4 by the bolts 78. Its oscillations operate the collapsible plates 41 through the levers 79 to drop the sheets of tin, placed thereon by the conveyor, to the table 18. It will be observed that the levers 79 are connected by short levers extending from collars on the shaft 75 and are likewise connected by short levers on shafts 82 upon which the collapsible plates 41 are mounted. Since a sheet 95 of tin is delivered during each rotation of the cam 65 there is one oscillation of the shafts 75 and 82 during the delivery of each sheet of tin. Accordingly the plates 41 are correctly timed to drop the respective sheets 100 of tin upon their delivery to the stacking machine.

The shaft 75 is also connected by lever 80 and arm 84, extending from the collar 85 on shaft 75, to arm 86 extending from a collar 87 loosely mounted on the shaft 25 operatively connected to the table supporting shafts 12. A pawl 88 mounted on the collar 87 engages an idling gear 89 and a drive gear 90 both mounted upon the shaft 25 to 115 rotate the same at predetermined periods, utilizing the oscillations of the shaft 75. Rotation of the gear 90 lowers the table 18 by turning the shaft 25 and bevel gears 26 and 27 which mesh with bevel gears 28.

120 While it is feasible to drop the sheets of tin, which are delivered by the conveyor from the collapsible plate 41 to the table 18 which may be mounted on a truck and which may be considerable distance from 130

the collapsible plate, it is nevertheless desirable to limit the distance that the tin is dropped to a minimum. For the automatic control of the table lowering mechanism associated with the lever 80 and pawl 81 to effect this end there is provided a pawl 91 attached to shaft 92 by arm 93 which is in turn mounted in bearings on the extensions 94 and 95. These extensions 94 and 95 are bolted to the brace member 8 and the upright members 4 respectively. A holder 96 for the pawl 91 is also mounted on the extension 94 to limit the downward movement of the same. The pawl 91 and idler gear 89 control the periods during which the table lowering mechanism is effective, and the periods during which it is ineffective, to move the table 18. The shaft 92 upon which pawl 91 is mounted is directly connected by the lever 103 to another shaft 97 mounted in bearings in the extensions 98 and 99 from the supporting member 10 and the vertical member 4 respectively.

The rocking of the shaft 97 and the consequent movement of the pawl 91 depends upon the operation of the cam 65 and the lever 72 (see Figs. 2 and 4) to which the shaft 97 is connected by means of lever 99, collar 100, and spring 101 associated with the lever 72. The collar 100 is slidably mounted on the lever 72 and is resiliently held in position by the spring 101 which rests against the adjustable nuts 102. As hereinbefore explained, the cam 65 is directly connected to the conveyor mechanism during the operation of the stacking machine through the clutch box 45; and it revolves and reciprocates the reciprocating head 68 continuously by means of the cam follower 69. The collar 100 mounted on the lever 72 likewise reciprocates rocking the shaft 97 except during the periods in which it is locked in position as hereinafter explained. It then slides on the lever 72 against spring 101 without oscillating shaft 97, lever 103, and shaft 92 associated therewith.

A locking mechanism for shaft 97 is shown in detail in Figures 11 and 12. It comprises a lever 104 rigidly mounted on shaft 97 by the lock bolt 105 and connected to a piston 106 adapted to reciprocate in a cylindrical aperture 107 in the supporting member 10. A feeler 108 rotatably mounted on an extension of the supporting member 10 is bolted to a bar 109 mounted in the piston 106. The bar 109 is ordinarily held in extended position by spring 110 resting against the seat 111, and mounted in a cavity 112 formed in the piston 106. During the reciprocation of the piston 106 occasioned by the reciprocation of the shaft 97 resiliently connected to the lever 72, the piston 106 reciprocates ordinarily with the bar 109 in extended position permitting the stop

115 to remain in its dotted position and thereby offering no impediment to the rocking of shaft 97. But when the tin 42 reaches a level higher than the end of feeler 108 as shown in Figure 11 the feeler engages the tin and prevents the bar 109 from moving with the piston 106, compressing the spring 110, and raises the stop 115 against spring 116 by means of the incline 117 and follower 118. The stop 115 when in raised position, as shown in Figure 11, prevents the reciprocation of piston 106, which in turn prevents the shaft 97 from rocking. The lever 103 operatively connecting shafts 97 and 92 is likewise held in position until the level of the tin has decreased below the level of feeler 108. The pawl 91 controlled by shaft 92 remains stationary and effective to prevent reverse rotation of the idler 89 but it does not during this period rotate the idler gear. Accordingly the pawl 81 is in operative engagement with the gear 90 and the table 18 is lowered a predetermined amount upon the delivery of each sheet of tin. A friction collar 120 having an inner band 121 is mounted on the idler gear 89 by means of the bolt 122 attached to the brace 8 to prevent free rotation of the idler gear. Suitable nuts 124 for adjustment of the collar 120 are provided.

It will be noted in the drawings that the idler gear 89 has a small slotted portion 125 without teeth, while the main drive gear has a continuous set of teeth. The pawl 81 is wide enough to engage the teeth of both the idler gear 89 and the main drive gear 90 and is reciprocated continuously during the operation of the stacking machine. The pawl 91 is reciprocated during the time that the stack of tin is below the level of the lower end of the feeler 108. Whenever the pawl 81 engages idler gear 89 it disengages from the gear 91 and the stack of tin ceases to move downwardly. When the pawl 91 is being reciprocated the idler gear is being rotated thereby and the pawl 81 can engage the drive gear 90 only for a very short period during its movement across the slotted portion 125 of the idler gear 89. Since the portion 125 is fairly small as compared with the circumference of the idler gear the period that the stack of tin is lowered is short, and the distance that the table is lowered is inappreciable in amount. But when the pawl 91 ceases to reciprocate, that is, when the stack of tin is above the end of the feeler 108 the pawl 81 continues to rotate the idler gear 89 until it reaches the portion 125 at which time it engages and rotates the gear 90, thereby lowering the stack of tin until the idler gear 89 is again rotated by the reciprocation of the pawl 91, that is until the stack of tin is below the feeler 108. The stack of tin is accordingly

maintained at a substantially constant height irrespective of the number or thickness of the sheets fed to the machine.

In certain instances it is desirable to manually control the lowering of the stack of tin by rendering the automatic control ineffective. This may be done by the hand throw-out 126 mounted on the shaft 25 between the gears 89 and 90. Raising the handle 127 on

10 the throwout 126 shifts a cam surface which raises and renders ineffective the drive pawl 81. It also pushes the toggle joint formed by the links 128 and 129 mounted on the extension 94 to the other side of its dead center until it rests against stop 130, also on extension 94. The spring 131 retains the toggle mechanism in the desired position, and the automatic table lowering mechanism is ineffective.

20 In order to prevent table 18 upon which the tin is stacked from being lowered to such an extent that a truck cannot be placed under it, rod 132 with a stop 134, adapted to be engaged by the table when it reaches a predetermined lower level, is loosely mounted on the shaft 92 and rigidly connected to the toggle mechanism which renders the lowering mechanism ineffective. The engagement of the table with the stop 134 rotates the hand throwout 127 and operates the toggle mechanism to disengage the table lowering mechanism, as hereinbefore described.

30 To facilitate the removal of the tin from the stacking machine without interfering with its operation, there is provided temporary stack supporting bars 135 slidably mounted in bearings 136 attached to the supporting members 10. A pair of shafts 137 having gears 138 adapted to mesh with racks 139 on the lower portion of the bars 135 move them into position to receive the tin while the table and stack of tin are being moved. They are, of course, moved out of position and the tin is permitted to drop to the table 18 when replaced. A hand wheel 143 is connected to one of the shafts 137 by chain 139' cog-wheels 140 and 141. It is connected to the other shaft 137 by shaft 142 and gears 145 and 138. The bars 135 may be moved into and out of position by manually rotating the wheel 143.

40 In the operation of the machine sheets of tin are placed upon the conveyor belts 39 and conveyor chains 34 which are moving toward the stacking machine 1. When the sheets reach the pulleys 40 the free edge of the tin contacts with the slides upon the collapsible members 41 until it reaches the stops 44. The conveyor mechanism being connected through the clutch box 45 to the cam 65 and the lever 68 the collapsible members 41 are caused to drop permitting the tin to fall upon the table 18 prior to the movement by the conveyor of another sheet upon

the collapsible members 41. Preferably the cam 65 makes one rotation during the time the conveyor travels a distance equal to the distance between two projections 36. As the sheets of tin are successively dropped from 70 the table 18 a stack is formed which continually increases in height and it is desirable to lower the table proportionately to the feeding of the tin in order to permit the tin to drop a minimum distance in each instance. 75

To accomplish this end and to lower the table at the required rate, the shaft 32 upon which the conveyor pulleys are mounted is directly connected to the cam 65 through the clutch box 45 which is likewise connected 80 through the lever 68, shaft 75, and lever 80 to a pawl 81 which is adapted to rotate the shaft 25 by engaging the ratchet gear 90 during each rotation of the cam 65. The shaft 25 is connected through bevel gears 26, 85 27, and 28 on the shafts 12 to lower the table a corresponding amount. Due to the fact that tin of different thickness is used at various times the conveyor mechanism and the table lowering mechanism cannot be so 90 geared that the table moves proportionately to the rise in height of the pile of tin. But on the other hand, the table will become too high or too low in the course of the operation of the stacking machine. There is accordingly provided an idler gear 89 on the shaft 25 and a pawl 91 adapted to engage the idler gear. This idler gear when rotated renders 95 ineffective the pawl 81 for rotating the shaft 25. Its operation is controlled by feeler 108 which is responsive to the height of the stack 100 of tin. The feeler 108 when it is above the level of the tin permits the shaft 97 to rock and this is communicated to the shaft 92 and the pawl 91 rotates the idler. But when the feeler 108 engages the top of the pile of tin the stop 115 is thrown out from its dotted position to lock the piston 106 and likewise the shaft 97. Accordingly the shaft 92 and the pawl 91 ceases to operate and the pawl 81 rotates the idler gear independently of the pawl 91 until the slotted portion 125 is reached, at which time it engages the drive gear 90 rotating the shaft 25 and lowering the table mechanism. When the table has 105 reached its lower limit it engages the stop 134 on the rod 132 and shifts the hand throwout 126 to render the pawl 81 ineffective. A truck is then placed under the table 18 and the table is lowered to the top of the truck by rotation of the hand wheel 19. Before the removal of the stack of tin thus lowered to the truck, the bars 135 are moved inwardly by the rotation of the hand wheel 143 and shafts 137 to form an auxiliary 110 table to retain the tin until table 18 has been replaced.

115 It will be seen that the present invention provides a stacking machine completely 120 automatic in all its operations and one in 125 130

which the human element is almost completely removed.

While the preferred embodiment of the present invention is described with reference to sheets of metal, it is not intended to be limited to such since it is equally applicable to sheets such as paper and the like and to many other classes of material. The description is to be taken as illustrative and not in a limiting sense as the scope of the invention is defined in the following claims.

Having thus described my invention, what I claim is:

1. In a machine of the class described, in combination, means for supplying sheet material, mechanism for receiving and stacking said sheet material, supporting means for said stack, devices for lowering said supporting means during the stacking operation, and reciprocating means adapted to engage the edges of the sheet at the top of said stack to render the lowering devices effective.

2. In a machine of the class described, in combination, a pair of upright members having shafts associated therewith, devices on said shafts for supporting a table, a table mounted on said devices, means for rotating said shafts to change the position of said table, means for supplying sheet material to said machine, and a pair of members for receiving said sheet material and stacking it on said table.

3. In a machine of the class described, in combination, a pair of upright members having shafts associated therewith, devices on said shafts for supporting a table, a table mounted on said devices, automatic means for rotating said shafts to maintain the top of said stack at a substantially constant level, means for supplying sheet material to said machine, and mechanism for receiving and stacking said sheet material on said table.

4. In a machine of the class described, in combination, a pair of upright members, a pair of cross members attached to said upright members to brace same and form a rigid supporting structure, said cross members having a substantial space therebetween, and means mounted on said cross members adapted to be moved into position to form a table.

5. In a machine of the class described, in combination, a pair of upright members, a pair of cross members attached to said upright members, means mounted permanently on said cross members and adapted to be moved into position to form a table, mechanism for supplying sheets of material to said machine, and devices for stacking said sheets on said table.

6. In a machine of the class described, in combination, a pair of upright channel members, a cross member attached to the

upper ends of said upright members, a bearing adjacent the upper and lower ends of each of said upright members, shafts extending through said channels and mounted in said bearings, a table mounted on said shafts, and means for varying the position of said table on said shafts.

7. In a machine of the class described, in combination, a pair of upright members having their upper ends joined by a cross member, a bearing adjacent the upper and lower ends of each of said upright members, vertical shafts mounted in said bearings, a table mounted on said shafts, automatic means for varying the position of said table with respect to said shaft.

8. In a device of the class described, in combination, a pair of upright members having their upper ends joined by a cross member, a bearing adjacent the upper and lower ends of each of said upright members, shafts mounted in said bearings, a table mounted on said shafts, a third shaft operatively connected to said first mentioned shafts to rotate same and thereby change the position of said table, and automatic means cooperating with said third shaft for lowering the table at a substantially constant rate.

9. In a machine of the class described, in combination, a pair of upright members having their ends joined by a cross member, a bearing adjacent the upper and lower ends of each of said upright members, shafts mounted in said bearings, a third shaft operatively connected to said other shafts to rotate same and thereby change the vertical position of said table, automatic means cooperating with said third shaft for lowering the table at a substantially constant rate, and means adapted to engage material on said table for rendering said automatic means effective when said table is at a predetermined level as determined by the height of said material.

10. In a machine of the class described, in combination, a pair of upright members having their upper ends joined by a cross member, a bearing adjacent the upper and lower ends of each of said members, shafts mounted in said bearings, a table mounted on said shaft, a third shaft operatively connected to said first mentioned shafts to rotate same and thereby change the vertical position of said table, automatic means cooperating with said third shaft for lowering the table at a substantially constant rate, and means for rendering said automatic means ineffective when said table is at a predetermined level.

11. In a machine of the class described, in combination, a conveyor mechanism for supplying sheet material, a pair of members for receiving said sheet material, means for positioning the sheets on said members, de-

vices for collapsing said members to drop said sheets, supporting means for receiving said sheet material when it is dropped, and means for changing the vertical height 5 of the supporting means to maintain the distance the sheets are dropped substantially constant.

12. In a machine of the class described, in combination, supporting means for sheet 10 material, devices for changing the position of said supporting means a continuously operative mechanism, resilient means for connecting said devices and said mechanism, and means engaging the edges of the sheet 15 material at the upper part of the side of the stack for retaining said devices in a substantially stationary position against the forces exerted by said resilient means thereby controlling the height of said supporting 20 means.

13. In a machine of the class described, in combination, a table for supporting sheet material, devices for changing the position of said table to maintain the upper portion 25 of the sheet material at a substantially constant level, a continuously operative mechanism connected to said devices, and reciprocating means engaging the edges of the sheet material and responsive to its upper level 30 to render said mechanism ineffective on said devices intermittently and thereby control the position of said table.

14. In machine of the class described, in combination, a table for supporting sheet material, devices for changing the position of said table, resilient means associated with said devices, a cam for giving an oscillatory motion to certain of said devices through the intermediation of said resilient means to 35 render said devices ineffective, and means responsive to the level of said sheet material for holding said devices stationary against the pressure applied by said resilient means to permit the continued operation 40 of said devices.

15. In a machine of the class described, in combination, a conveyor for supplying sheet material, a stacking mechanism, a table upon which said material is stacked, 50 devices for regulating the height of said table to correspond inversely to the height of the stack, a rotating shaft operatively connected to said conveyor, and having a cam thereon, a lever associated with said stacking mechanism and having a rider thereon cooperating with said cam, said cam being adapted to give an oscillatory movement to said lever, and resilient means for operatively connecting devices to said lever. 55

16. In a machine of the class described, in combination, a conveyor for supplying sheet material, a stacking mechanism, a table upon which said material is stacked, devices for regulating the height of said

table, a rotating shaft connected to said conveyor and having a cam thereon, a lever associated with said stacking mechanism and having a rider thereon cooperating with said cam, said cam being adapted to give an oscillatory movement to said lever, 65 resilient means for operatively connecting said devices to said lever, and means responsive to the level of said material to render said resilient means ineffective. 70

17. In a machine of the class described, in combination, a conveyor for supplying sheet material, mechanism for stacking said material, a table for supporting said stack, devices for lowering said table, means for connecting said devices and said mechanism to lower said table a predetermined distance as each sheet is placed upon the stack, and an idler adapted to supplant said connecting means and render said stacking 75 mechanism ineffective on said table lowering 80 means.

18. In a machine of the class described, in combination, a conveyor for supplying sheet material, mechanism for stacking said material, a table for supporting said stack, 85 devices for lowering said table, means connecting said devices and said mechanism to lower said table a predetermined distance as each sheet is placed upon the stack, an idler adapted to supplant said connecting 90 means and render said stacking mechanism ineffective on said table lowering mechanism, and means responsive to the level of said sheet material for interchanging said connecting means and said idler. 95

19. In a machine of the class described, in combination a stacking mechanism for sheet material, means for supporting said stack, devices for controlling the vertical height of said support comprising a gear 100 operatively connecting said supporting means to lower same upon rotation thereof, an idler associated with said gear, means for operatively connecting said stacking mechanism with said gear to rotate same a predetermined amount as each is placed upon the stack, and means controlled by the level of the top of the stack to connect said stacking mechanism to the idler and thereby render it substantially ineffective on 105 said gear. 110

20. In a machine of the class described, in combination a stacking mechanism for sheet material, means for supporting said stack, devices for controlling the vertical height 115 of said supporting means comprising a gear operatively connecting said supporting means to lower same upon rotation thereof, an idler associated with said gear, means for operatively connecting said stacking mechanism with said gear to rotate same a predetermined amount as each sheet is placed on the stack, means controlled by the 120

- level of the top of the stack to connect said stacking mechanism to the idler and thereby render it substantially ineffective on said gear, and adjustable means for increasing 5 the resistance of said idler to rotation.
21. In a machine of the class described, in combination, a stacking mechanism for sheet material, means for supporting said stack, devices for changing the height of 10 said supporting means, comprising a gear operatively connecting said supporting means to lower same upon rotation thereof, an idler associated therewith, a pawl operatively connecting said stacking mechanism 15 with said gear to rotate same a predetermined amount as each sheet is placed on the stack, and means for engaging said pawl with said idler to render it substantially ineffective on said gear.
22. In a machine of the class described, in combination, means for supporting sheet material, mechanism for receiving and stacking said sheet material, supporting means for said stack, devices for lowering 20 said supporting means, and reciprocating means engaging the edges of the stacked sheets when above a predetermined level to render said devices effective.
23. In a machine of the class described, in combination, means for supporting sheet material, mechanism for receiving and stacking said sheet material, devices for lowering said supporting means, and a reciprocating feeler adapted to engage the 25 side of the stack, said feeler being operative to render said lowering devices ineffective when the top of the stack is too low to be engaged thereby.
24. In a machine of the class described, 30 the combination of means for supplying sheet material, mechanism for receiving and stacking said sheet material, supporting means for said stack, devices for lowering said stack supporting means, and means en-
- gaging the edges of the stacked sheets to 35 permit said devices to lower said supporting means at one speed when the top of said stack is above said engaging means and at a slower speed when below it.
25. In a machine of the class described, 40 in combination, means for supplying sheet material, mechanism to receive the respective sheets and drop them vertically to a stack, a table for supporting said stack, devices to lower said table, and controlling means for said devices adapted to engage the side of the stack to render said devices effective.
26. In a sheet handling machine, means 45 for supporting a stack of sheet material, devices for varying the height of said supporting means, and a horizontal reciprocating feeler located at the side of the stack adapted to engage the edges of the sheets at the top of said stack to control said devices.
27. In a sheet handling machine, means for supporting a stack of sheet material, devices for varying the height of said supporting means, mechanism adapted to render said devices ineffective, and means comprising a reciprocating feeler adapted to engage the edges of the sheets to lock said mechanism in ineffective position when the top of said stack is above a predetermined level so that said devices may change the 75 height of said supporting means.
28. In a sheet handling machine, means for supporting a stack of sheet material, devices for varying the height of said supporting means, mechanism adapted to render 80 said devices ineffective, and a horizontally reciprocating feeler, said feeler being adapted to lock said mechanism upon engagement with the side of the stack to permit said devices to vary the height of said supporting 85 means.
29. In a machine of the class described, in combination, a pair of upright supporting members, a pair of horizontal bracing members attached to said upright members, a vertically adjustable table, means for receiving and stacking sheet material on said table, and a plurality of bars mounted in 90 said bracing members and adapted to be moved horizontally into position to form a temporary table for holding the sheet material while said first mentioned table is being moved.
30. In a sheet handling machine, the combination of a table for supporting sheet material a pawl adapted to change the position of said table, a reciprocating lever adapted to operate said pawl to move said table continuously, devices to render said pawl ineffective, resilient means on said lever adapted 100 to operate said devices, and mechanism responsive to the height of said sheet material for rendering said resilient means ineffective.
31. In a sheet handling machine, in combination, a table for supporting sheet material, a pawl adapted to change the position of said table, a reciprocating lever adapted to operate said pawl, a continuously rotating shaft having a collar thereon adapted to reciprocate said lever, a collar mounted on said lever, resilient means for holding said collar in position, devices operatively connected to said collar to render said pawl ineffective when said collar reciprocates with said lever, and means responsive to the level 110 of said sheet material for locking said collar in position.
32. In a machine of the class described, in combination a conveyor mechanism for supplying sheets of tin and the like, a pair of members to receive said sheets individually, devices to collapse said members to drop individual sheets therebetween, a supporting table for receiving said sheets when 115
- 120
- 125
- 130

- dropped, and automatic means for changing the height of said table to maintain the top of the stack at a substantially constant level.
33. In a machine of the class described, in combination, a pair of upright supporting members, bracing members attached to said upright members forming a rectangular space to accommodate a stack of sheet material, collapsible members mounted on said bracing members and adapted to receive sheets, means for collapsing said members when a sheet is delivered thereto, and a table for receiving and supporting the sheets dropped by said collapsible members.
34. In a machine of the class described, the combination of means for supporting sheet material, mechanism for receiving and stacking said sheet material, devices for lowering said supporting means, a feeler adapted to be reciprocated into engagement with the side of the stack to control said lowering devices.
35. In a machine of the class described, the combination of means for supporting sheet material, mechanism for receiving and stacking said sheet material, devices for lowering said supporting means, and a feeler adapted to be reciprocated horizontally over the top of said stack to engage the upper edge thereof when above a predetermined level to control the lowering devices, said feeler permitting the sheets of material to fall vertically upon the top of the stack.
36. In a machine of the class described, the combination of means for supporting sheet material, mechanism for receiving and stacking said sheet material, supporting means for said stack, devices for lowering said supporting means during the stacking operation, and a feeler adapted to engage the edges of the sheets at the top of said stack to render the lowering devices effective when the top of the stack is above a predetermined level and adapted to pass across the top of the stack to render the lowering devices ineffective when the top of the stack is below a predetermined level.
37. In a sheet handling machine, the combination of a pair of upright members having their upper ends joined by a cross member, a bearing adjacent the upper and lower ends of each of said upright members, shafts mounted in said bearings, a table mounted on said shafts, a third shaft operatively connected to said first mentioned shafts to rotate same and thereby change the position of said table, and automatic means cooperating with said third shaft for changing the position of said table at a substantially constant rate.
38. In a sheet handling machine, the combination of means for handling sheet material, means for supporting a stack of sheet material adjacent said sheet handling means, devices for changing the position of said supporting means to change the height of said stack, and means engaging the edges of the stack sheets to permit said devices to change the height of said supporting means at one speed when the top of said stack is above the level of said engaging means, and at a slower speed when below it.

ABRAHAM PODEL.
